Fig. 5

Figure 1 is a front elevational view of an adjustable electric power supply, showing my new design;

Fig. 2 is a rear elevational view;

Fig. 3 is a top plan view;

Fig. 4 is a side elevational view, the opposite side being substantially a mirror image thereof; and

Fig. 5 is a bottom plan view thereof.

The dominant feature of my design resides in the stacked cylindrical units being aligned and spaced from each other with a rectangular housing combined therewith to extend continuously along the cylindrical units, said housing being narrower than and projecting a substantial distance outwardly from the cylindrical units.

I claim:

The ornamental design for an adjustable electric power supply, as shown and described.
